UNITED STATES PATENT OFFICE.

CARL A. RAUSCH, OF LEIPZIG-GOHLIS, GERMANY, ASSIGNOR TO FORTUNA-WERKE
SPECIALMASCHINENFABRIK, G. M. B. H., OF STUTTGART-CANNSTATT, GERMANY,
A FIRM.

BOARDING-MACHINE.

1,232,975.

Specification of Letters Patent. Patented July 10, 1917.

Application filed June 15, 1915. Serial No. 34,273.

To all whom it may concern:

Be it known that I, CARL A. RAUSCH, of 13 Roscherstrasse, Leipzig-Gohlis, in the Kingdom of Saxony, German Empire, civil 5 engineer, have invented certain new and useful Improvements in Boarding-Machines, of which the following is a specification.

My invention relates to boarding machines and more especially to machines of the kind 10 where the folded-up hide is rolled to and fro between two plates at the fold. The object of my invention is to provide a boarding plate for machines of this class which will adapt itself easily to the differences in 15 thickness of each hide and which will nevertheless avoid the drawbacks presented by former machines designed to accomplish the same results.

In the machines hitherto in use the boarding plates, in order to allow them to adapt 20 themselves to the differences in the thickness of different parts of a hide, were composed of a number of smaller plates, rigid in themselves but movable relatively to each 25 other, each plate being supported by an elastic support such as a spring or the like and liable to recede or to assume an oblique position. This arrangement however has proved to give bad results on account of the 30 joints between the single plates producing stripes or furrows in the hide to be boarded, thus rendering it inferior in quality.

In the boarding machine according to my 35 invention these drawbacks are avoided by employing boarding plates presenting a continuous working surface although fully adapting themselves to the inequalities of the hides. In order to obtain this result the boarding plate is composed of two parts, 40 viz. the working plate proper consisting of a rather soft and very elastic material such as cork, and a supporting plate of an equally elastic but more rigid material such as thin wood, steel or the like. The two plates are 45 supported in their turn by a number of springs juxtaposed at certain distances all along the bottom surface of the supporting plate, said springs being adapted to be adjusted according to the varying average 50 thickness of each hide.

The drawings annexed to this specification show the preferred form of a boarding device according to my invention.

In the drawings—

Figure 1 is a longitudinal section,

55

Fig. 2 is a plan view, and

Fig. 3 is a cross section, on an enlarged scale, of a boarding device according to my invention.

Fig. 4 is a plan view, on a scale equal to 60 the one adopted in Fig. 3, of the shaft and springs designed to adjust the boarding plate proper.

Figs. 5 to 7 are details of construction.

1 is the top part of the composition boarding plate and 2 is the bottom part or supporting plate. Plate 1 consists of cork or of any other suitable elastic material and should preferably be made in one piece, but in view of its being supported by the continuous plate 2 it may as well be composed of a number of juxtaposed smaller plates preferably joined together.

The elastic bottom plate 2 is preferably made of a thin wooden plate built up of a 75 number of thin boards glued up cross-wise and presenting a very great elasticity in all directions. This bottom plate is in its turn supported by a number of laminated springs 3, each spring being composed of three or 80 more flat springs held together by a screw 4 and fastened to a block 5 fixed to a shaft 6 common to all the laminated springs. Shaft 6 is supported near its ends in vertically slotted bearings 7 fastened to the 85 bottom of a casing 8 surrounding the shaft 6, the springs 3 and the supporting plate 2. Cams 9 fixed on the shaft 6 near its ends and resting against the bottom of the casing and a lever 10 at its free end projecting 90 through the casing outward enable the operator to lift the shaft toward the boarding plates and to control thereby the degree of compression of the springs supporting same as well as the degree of rigidity imparted to said plate. The springs on account of their being fastened to a common shaft can easily be removed from the casing and be replaced by stronger springs if necessary.

By providing the lever 10 with 100 a pawl 11 gliding on a toothed segment (not shown) the shaft may be fixed in any position. The free ends of the springs 3 supporting the bottom plate 2 are guided between projections 12 provided on the bottom 105 face of said plate.

The plates 1 and 2 are prevented from being expelled from the casing 8 by angle irons 13 fastened to the free side edges of said casing, at least one of said angle irons 5 being removably fastened in order to facilitate the temporary removal of the boarding plate and springs. To this effect screws 14 are screwed into the side wall of casing 8 and pins 15 fastened to the angle iron are provided, the heads of the screws 14 projecting through slots, open at one end, of the angle iron, while the pins 15 pass through both the casing wall and the angle iron and screws and pins alternating with each other. 10 In order, now, to remove the angle iron, the screws 14 need only be loosened far enough to allow the pins 15 to be withdrawn from the perforations provided in the wall of the casing. By this arrangement a total 15 removal of the screws frequently resulting in the loss of the screws is avoided.

I claim:

1. In a boarding machine, in combination, a boarding plate consisting of a soft and 25 elastic working plate and a hard and elastic supporting plate, and a row of springs adapted to support said supporting plate and to exert a variable pressure upon the boarding plate.
2. In a boarding machine, in combination, a cork plate, a thin hard elastic plate adapted to support said cork plate and springs adapted to support said supporting plate and to exert a variable pressure upon the boarding plate. 30
3. In a boarding machine, in combination, a continuous cork boarding plate, a continuous thin hard elastic supporting plate, and springs adapted to support said supporting plate and to exert a variable pressure upon the boarding plate. 40
4. In a boarding machine, in combination, a continuous boarding plate, a continuous

supporting plate fastened to it, a plurality of juxtaposed springs adapted to support 45 said supporting and boarding plates, said springs being fixed to a common shaft, cams on said shaft, an abutment for said cams and means for rotating said shaft so as to shift the springs in the direction toward 50 said plates.

5. In a boarding machine, in combination, a continuous boarding plate, a continuous supporting plate fastened to it, a plurality of juxtaposed springs adapted to support 55 said supporting and boarding plates, said springs being fixed to a common shaft, cams on said shaft, a casing surrounding the shaft and the springs, the bottom part of said casing serving as an abutment for the cams on said shaft and a lever fixed to said shaft and adapted to rotate it and to shift it and the springs in a direction away from the bottom of said casing. 60

6. In a boarding machine, in combination, 65 a continuous boarding plate, a continuous supporting plate fastened to it, a plurality of juxtaposed springs adapted to support said supporting and boarding plates, said springs being fixed to a common shaft, cams on said shaft, a casing surrounding the shaft and the springs, the bottom part of said casing serving as an abutment for the cams on said shaft, a lever fixed to said shaft and adapted to rotate it and to shift it and the 70 springs in a direction away from the bottom of said casing, and angle irons removably fastened to the side walls of said casing and overlapping the side edges of said supporting plate. 75

In testimony whereof, I affix my signature, in presence of two witnesses.

CARL A. RAUSCH.
